(57) **CLAIM**

The ornamental design for a display screen as shown and described.

DESCRIPTION

FIG. 1 is a front, right, top perspective view of a display screen showing our new design in a first state in which the display screen is flat;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right, top perspective view of the display screen in a second state in which the display screen is curved;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof; and,

FIG. 15 is an enlarged view of portion “15” of FIG. 1.

The broken lines depict portions of the display screen that form no part of the claimed design. The dot-dot-dash broken lines in FIGS. 1 and 15 are included to show the boundary of the enlarged view and form no part of the claimed design.

1 Claim, 15 Drawing Sheets
